PORTABLE STOOL FOR A FISHERMAN

Charlie S. Otto, 106 Dicey Road,
Weatherford, Tex. 76086

Filed Sept. 2, 1966, Ser. No. 3,703

Term of patent 3½ years

(Cl. D15—8)

FIG. 1 is a perspective view of a portable stool for a fisherman embodying my new design, with its leg partially folded toward a carrying position;

FIG. 2 is a left side elevational view thereof;

FIG. 3 is a right side elevational view thereof;

FIG. 4 is a front elevational view of my fishing stool, with its leg folded completely outward; and

FIG. 5 is a plan view as seen from the bottom of my fishing stool, with its leg folded inward to the carrying position and its handle rotated outward.

The dominant features of my design reside in those portions shown in full lines on the drawing.

I claim:

The ornamental design for a portable stool for a fisherman, as shown and described.
